UNITED STATES PATENT OFFICE.

JOSEPH M. SPINDLER, OF SHAKOPEE, MINNESOTA.

VENDING-MACHINE.

No. 866,742.

Specification of Letters Patent.

Patented Sept. 24, 1907.

Application filed February 11, 1907. Serial No. 356,708.

To all whom it may concern:

Be it known that I, JOSEPH M. SPINDLER, a citizen of the United States, residing at Shakopee, in the county of Scott and State of Minnesota, have invented 5 a new and useful Improvement in Vending-Machines, of which the following is a specification.

- My invention relates to improvements in vending machines and has for its primary object to vend articles of merchandise such as cigars and tobacco.
- 10 By this invention the user can extract or select and obtain any desired article from a number of different grades and classes of goods.

In a general way, this invention comprises a magazine held within a frame and having a series of holders 15 for the articles to be vended and a cut-out operated by hand and brought into coaction with said magazine by coin-operating or other suitable mechanism for the purpose of extracting the article desired from the machine. The article desired according to grade or class 20 is selected by turning the magazine and causing it to register with the cut-out which when moved extracts the article. The coin-operating mechanism connects and disconnects with the cut-out so that it can be used only when a coin is brought into play.

25 A further object in view is the production of a machine for vending articles of different classes in which a single cut-out is used and which is simple and compact in construction and effective in operation.

In the accompanying drawings, forming part of this 30 specification Figure 1 is a side view of my invention showing part of the frame broken away to expose the interior mechanism to view; Fig. 2 is a plan view of Fig. 1 partly broken away; Fig. 3 is a plan view looking down upon the table showing the vertical shaft in section; Fig. 4 is a view looking up at the table, the shaft 35 being shown in section; Fig. 5 is a detail view looking down upon the cut-out; Fig. 6 is a side view of Fig. 5 and Fig. 7 is a detail view showing an alternate construction by which bags of tobacco or other commodities 40 may be held upon the table.

In the drawings A represents the frame of the machine which in plan view appears as a substantially irregular hexagon. The sides 2 of this frame are provided with lights of glass 3 so that the magazine is 45 visible.

The construction provided has two prime elements, a magazine A and a cut-out B. The magazine consists of a horizontal tray 4 which is mounted and supported upon a vertical shaft 5 passing centrally there- 50 through, by means of braces 6. The lower end of this shaft is journaled in a step bearing 7 and its upper end passes through a journal bearing 8 and is provided with a handle 9 outside of the inclosing frame A. The bearings are carried by an angle iron 10 which also serves the 55 purpose of reinforcing the frame and is fastened thereto by means of bolts 11.

Distributed around the table are a series of sets of clamps 12 which are provided with set bolts 13 between which cigar boxes containing cigars to be vended are held upon the tray. These boxes are placed endwise 60 upon the table with their lower ends removed. The upper clamp is supported by a sectional bracket 14 which is adjusted vertically in height by means of the set bolt 15. When the cigar boxes are placed upon the tray their lids may be opened and a plate of glass 16 65 inserted as shown in Fig. 2 so that the contents of the box and the label on the back of the cover can be inspected. Detents 17 on the upper set bolt 13 and tray 4 limit the movement of the lid and assist in holding the plate of glass 16 in place.

70 The tray is provided with openings 18 below the lower end of each cigar box through which the cigars in the boxes are adapted to pass. Normally these openings are closed by means of shutters 19. Ultimately the cigars as they are vended from the machine 75 drop through the opening 18 in the tray into a chute 20 which projects through the inclosing wall of the frame A. This chute extends so that the cigars when sliding down it turn into a longitudinal position as they egress from the machine.

80 Interposed between the upper end of the chute and the tray is the cut-out B. This cut-out has a slide 21 which works between gibs 22 and in a projecting portion 23 at the front end of the frame A. A handle 24 on the outer end of the slide works through the wall of the projecting portion 23 of the frame and by its use the slide is reciprocated. A slot 25 in the slide 21 when pushed in is adapted to correspond with the opening in the upper end of the chute 20 and the tray 4 can be swung with any one of its openings over said slot when 90 desired. When the slide is in receded position the openings in the tray and chute are not in its path. The shutters 19 on the table slide in grooved pieces 26 and are provided with depending flanges 27 which when the table is revolved pass through a groove 28 in the 95 upper face of the slide 21. When the table is stopped with one of the openings 18 in line to register with the chute and the slide 21 moved, the sides of the groove 28 are adapted to impinge against one of the depending flanges 27 and open and close the shutter 19 which is 100 engaged.

Should the table be stopped when one of the openings 18 is not in line to register with the chute, lugs 29 on the bottom of the table engage the slide 21 in the slot 30 and prevent it moving. When the table is in registering position as described, the slide 21 105 passes freely between the lugs 29.

Below the slide 21 and extending across the slot 25 when the slide is brought into position to register with one of the openings in the table and the chute is a plate 31 which is pivoted upon the frame of the machine. 110 This plate rests horizontally within a recess 33 in the slide 21 and is counter-balanced by means of the weight

34 so that its free end presses upward against the slide 21 and closes its opening 25 when the slide is drawn out. The article vended thus drops through the slot in the slide 21 and on to the plate 31 which it depresses until 5 eventually the article drops into the chute 20. A finger 35 on one edge of the plate 31 comes into contact with a dog 36 on the frame of the machine which prevents the slide being closed in case the article does not drop out of the magazine. In this manner the article 10 being vended can be cleared from the machine and the slide operated which insures the delivery of the article. If the article being vended tilts the plate down it also operates the dog 36 which carries a pin 37 working in a slot 38 in one of the side bars 32 to limit the movement 15 of said dog. The dog is pivoted at 38' and is provided with a stop shoulder 39 to prevent the movement of the slide 21.

Cooperating with the slide 21 is a coin-operating mechanism C which controls its action. This coin 20 operating mechanism is provided with a coin track 40 which conducts the coins from the exterior wall of the inclosing frame and drops them into a receiver 41. This receiver is supported upon a balance arm 42 which is pivoted at 43 upon the frame of the inclosure. The 25 free end 44 of the balance arm is adapted to strike the pin 45 working in the groove 46 of the side bar 32 and carried by the dog 47. This dog 47 has a stop shoulder 48 normally in the path of the stop 49 on the edge of the slide 21 and prevents the slide moving until the dog 30 47 has been tilted down by the balance arm as described. The coin is released from the receiver by means of the trip 50 which turns longitudinally in the coin receiver and has its lower end 51 intercepting the path of the coin. The upper end of the trip 50 is moved 35 by the slanting shoulder 54 on the slide. The weight of the trip holds it normally in position to hold the coin in the receiver. A post 52 supports the free end of the balance arm and a weight 53 counter-balances the coin receiver.

40 If the tray of the magazine is provided with articles of different value, for illustration, if the articles in part of the cases are valued at ten cents each while the articles in the cases on the remaining portion of the tray are valued at five cents, an extension 55 on the 45 free end of the balance arm 42 is provided against the upper end 56 of which hinged weights 57 which are also provided adjoining the cases on the tray containing the articles of merchandise are adapted to sweep, thus requiring that two five cent coins or double the weight 50 be passed into the receptacle 41 before the balance arm 42 is depressed and its upper end swung out of the path of the stop 49. When the magazine is used for vending sacks of tobacco or other commodities it may be provided with vertical holders 60 which are fastened 55 upon the tray by means of clips 61 as shown in Fig. 7.

In operation, the boxes of cigars to be vended are clamped upon the tray and when it is desired to operate the machine, a coin is rolled down the coin track. The magazine is turned until the article it is desired to vend 60 is in line to register with the chute. The slide is then withdrawn and returned into the machine, whereupon the article to be vended drops through the slot in the slide and into the chute 20 through which it egresses from the machine.

65 While I have described my apparatus as applied for

use for vending cigars and tobacco, it is obvious that the same may be utilized for vending other articles and commodities and the construction variously modified within the spirit of the specification and of the following claims.

70

Having described my invention, what I claim as new and desire to protect by Letters Patent is:—

1. A machine of the class set forth, comprising, in combination an inclosing frame, a tray journaled in said frame and provided with means for detachably holding 75 different articles to be vended and a series of openings through which said articles are adapted to pass, a cut-out co-acting with said magazine and adapted to register with a single one of said openings at a time, lugs on said tray between which said cut-out is adapted to slide and preventing it from being operated except when registering with a single opening and a check plate below said cut-out, for the purposes specified.

2. A machine of the class set forth, comprising, in combination an inclosing frame, a tray journaled in said frame and provided with detachable means for holding 85 a series of different articles to be vended, and a series of openings, a cut-out co-acting with said magazine below said openings, means for turning said magazine and causing it to register with said cut-out at different openings 90 during its movement, lugs on said tray adapted to engage said cut-out and permitting it to be withdrawn when registering with a single one of said openings and a check plate below said cut-out, for the purposes specified.

3. A machine of the class set forth, comprising, in combination, an inclosing frame, a magazine journaled in said frame, a series of containers in said magazine, clamps detachably holding said containers in said magazine, means for revolving said magazine, a cut-out with which said magazine is adapted to be brought into communication, means for preventing the movement of said cut-out and means for checking the advance of articles passing through said cut-out, for the purposes specified.

4. A machine of the class set forth, comprising, in combination, an inclosing frame, a magazine journaled in said frame, and provided with means for holding different priced articles to be vended, a cut-out co-acting with said magazine and adapted to remove a single article at a time therefrom, means for turning said magazine, means for permitting the movement of said cut-out, and a check plate pivoted below said cut-out, and means for normally pressing said plate up to close the opening in said cut-out.

5. A machine of the class set forth, comprising in combination, an inclosing frame, a vertical shaft journaled in said frame, means over said frame for turning said shaft, a tray supported by said shaft, and provided with a series of openings therein arranged circumferentially around said shaft, a series of slides for supporting articles to be vended above said openings and upon said tray, means for operating said slides, a manually operated one piece cut-out having a slot below the path of the openings in said tray, and a handle extending from said frame for reciprocating said cut-out.

6. A machine of the class set forth, comprising, in combination, an inclosing frame, a vertical shaft journaled in said frame, means for turning said shaft, a tray supported by said shaft and provided with a series of openings therein, means for supporting a series of articles to be vended above said openings and upon said tray, a slide having a slot below the path of said openings, a chute leading from below said tray and with which the slot in said slide is adapted to register, and a check plate above the entrance into said chute, for the purposes specified.

7. A machine of the class set forth, comprising, in combination, an inclosing frame, a revolvable magazine journaled in said frame and having a series of openings, separate slides adapted to close each of said openings, adjustable clamps for holding articles in said magazine, a single piece cut-out below said magazine, having a slot through which articles from the magazine are adapted to pass, a dog adapted to hold said cut-out closed, a check plate below said cut-out adapted to prevent it being closed except when the article being vended falls thereon; said

cut-out being provided with a pair of grooves, one of which causing said cut-out to engage a slide and open it, a series of lugs below said magazine adapted to pass through the other groove in said cut-out and prevent the 5 operation of the machine when the magazine is not in proper position, a hand grip above said frame for turning the magazine, and a chute below the check plate through which the articles are adapted to pass.

8. A machine of the class set forth, comprising, in combination, an inclosing frame, a magazine journaled in said frame, and provided with a series of openings therein, means for supporting articles to be vended adjoining said openings, a slide having a slot below the path of

the openings in said magazine, a chute below the path of said openings, and a check plate below the slot in said 15 cut-out and above the entrance into said chute and adapted to permit the articles vended to pass into said chute, and means for limiting the movement of said cut-out.

In testimony whereof, I have signed my name to this 20 specification, in the presence of two subscribing witnesses.

JOSEPH M. SPINDLER.
